UNITED STATES PATENT OFFICE.

AUGUST W. KURZ, OF CLEVELAND, OHIO.

DESIGN FOR A CATCH-BASIN INLET.

SPECIFICATION forming part of Design No. 35,535, dated December 31, 1901.

Application filed November 15, 1901. Serial No. 82,457. Term of patent 14 years.

To all whom it may concern:

Be it known that I, AUGUST W. KURZ, a citizen of the United States, residing at Cleveland, in the county of Cuyahoga and State of Ohio, have invented and produced a new and original Design for Catch-Basin Inlets; and I do hereby declare the following to be a full, clear, and exact description of the same, reference being had to the accompanying drawings, forming a part thereof.

In the drawings, Figure 1 is a top plan view of the catch-basin inlet, and Fig. 2 is a vertical section thereof on the line 2 2 of Fig. 1.

The leading features of my design consist of the circular base, the vertically-extending angular portion having one of its sides rounded, the rounded side portion extending above the plane of the angular portion and inclined relatively thereto, and the vertically-extend-

ing mouth portion surmounting the inclined portion.

5 designates the circular base; 6, the vertically-extending angular portion; 7, the rounded side portion, having the inclined portion 8, and 9 the vertically-extending mouth 25 portion.

10 designates a grating having substantially square openings.

I claim—

The design for a catch-basin inlet, substantially as shown and described.

In testimony whereof I have affixed my signature in presence of two witnesses.

AUGUST W. KURZ.
